**ACTUATING MEANS FOR TOILET SEATS
AND LIDS**Kenneth Newkirk, 866 Green St.,
San Francisco, Calif. 94133Continuation-in-part of application Ser. No. 343,659,
Feb. 10, 1964, now Patent No. 3,316,561, dated
May 2, 1967. This application Oct. 31, 1966, Ser.
No. 590,565

5 Claims. (Cl. 4—251)

ABSTRACT OF THE DISCLOSURE

A device for returning a toilet seat and lid to a closed position including hydraulic timing means actuated upon opening of the seat or lid to a vertical position. Holding means is provided for holding the seat or lid in an open position for a predetermined interval of time after which a separate closing means swings the seat or lid toward closed position and at the same time slows movement to such closed position.

This application is a continuation-in-part of application Ser. No. 343,659 filed Feb. 10, 1964 since matured into Patent No. 3,316,561, dated May 2, 1967.

This invention relates to toilet seats and toilet seat lids and more particularly to a mechanism for automatically returning the seat and lid to a horizontal closed position so that the fixture has a neat appearance at all times when not in use.

The above cited patent application discloses a mechanism for both opening and closing the seat and lid. The present invention is directed to a mechanism for automatically closing the seat and lid after the same have been opened manually.

The main object of the invention is the provision of a relatively inexpensive foolproof mechanism by which the toilet seat and lid are automatically lowered to a closed position when not in use.

Other objects and advantages of the invention will be apparent from the following specification and from the drawings:

FIG. 1 is a fragmentary top plan view of a toilet bowl showing the manner in which the invention is installed thereon.

FIG. 2 is a fragmentary side elevation of the structure of FIG. 1.

FIG. 3 is a top plan view of the mechanism constituting the invention shown in its inoperative position.

FIG. 4 is a rear elevation of the mechanism of FIG. 3.

FIG. 5 is a vertical sectional view taken in a plane indicated by line 5—5 of FIG. 3.

FIG. 6 is a fragmentary side elevation showing the seat and lid in raised position.

FIG. 7 is a fragmentary side elevation showing the lid only in raised position with the seat in down position.

FIG. 8 is a fragmentary side elevation showing the seat and lid in a slightly raised position when both seat and lid are being raised together.

FIG. 9 is an enlarged view of the mechanism in the same inoperative position as in FIG. 4.

FIGS. 10—12 are views similar to FIG. 9 but showing the mechanism in successive positions during the raising and lowering cycle.

FIG. 13 is a vertical cross section of the hydraulic unit.

FIG. 14 is a cross section taken in a plane indicated by lines 14—14 of FIG. 13.

FIG. 15 is a fragmentary cross section taken in a plane indicated by lines 15—15 of FIG. 3.

2

In detail, and first with reference to FIGS. 1 and 2, the invention is adapted to be employed with a conventional toilet bowl generally designated 1 which is provided with the usual toilet seat generally designated 2 and lid 3. The mechanism of the present invention takes the form of a relatively small unit which may be placed rearwardly of the seat and lid and supported on the upwardly facing surface of the bowl and secured thereto by passing bolts through the existing holes in the bowl body which normally support the shaft on which the seat and lid are swingable.

As best seen in FIGS. 3, 4 the unit may be mounted on a base plate 4 to which are secured a pair of upwardly extending bearings 6, 7 on which a shaft 8 is rotatably supported. The lid 3 is provided with a pair of brackets 10, 11 which are fixedly secured by bolts 12, 13 to the main shaft 8.

For a reason which will be pointed out later the seat 2 is not integrally connected to shaft 8 but is provided with a flat bracket 15 which is formed along its opposite side edges with a pair of opposed upwardly directed lugs 16, 17 which are connected at their upper ends by a horizontally extending rod 18. Lugs 16, 17 are provided with relatively large elongated apertures 20 for receiving therethrough the main shaft 8. At spaced points along the length of rod 18 and shaft 8 there are provided a pair of circular springs 21, 22 which, as best seen in FIG. 15, yieldably connect rod 18 to shaft 8.

At this point it may be noted that upon upward swinging of lid 3 the shaft 8 to which it is connected will rotate in bearings 6, 7. However upon upward swinging of both the seat and the lid means is provided for interconnecting the two automatically. As best seen in FIGS. 5—8 lid brackets 10, 11 are provided with upwardly projecting extensions 23 which, when the lid only is raised as seen in FIG. 7, clears the rod 18. However when both the seat and lid are raised as shown in FIG. 8 the rear end of bracket 15 moves downwardly relative to the shaft 8 carrying with it the rod 18 so that the extensions 23 butt against the rod 18 thus interconnecting the seat and lid which remain interconnected until lowered to the down position. Secured to the underside of seat 2 adjacent its rear end are a pair of yieldable bumpers 25 on which the seat pivots so as to raise the bracket 15 to its up position as seen in FIG. 7, thus permitting the lid to be raised alone if this is desired.

Referring again to FIGS. 3 and 4 there is provided at one end of shaft 8 a bevel gear 26 which is in mesh with a pinion 27 rotatably supported on a bearing pin 28 which is in turn mounted on the vertically extending leg 29 of a bearing bracket 30. Fixedly secured to pinion 27 for rotation therewith is a driving arm 31 which extends radially outwardly from pinion 27 and which is provided at its outer end with a driving pin 32. Driving pin 32 extends through slots in a release lever 33 and an actuating cam 34 and pivotally supports at its end a cocking lever 35. This cocking lever 35 is adapted to cooperate with a timing cam 36 to which is secured a cocking pin 37. As best seen in FIGS. 9—12, upon counterclockwise rotation of pinion 27 and driving arm 31 cocking lever 35 is moved to the left as seen in FIG. 9 so that the hooked end 38 of the cocking lever engages cocking pin 37 on timing cam 36 urging the latter to the left.

Timing cam 36 is connected by means of a pivot pin 39 with the outer end of a piston rod 40 of a hydraulic unit generally designated 41. The hydraulic unit 41 will be described in greater detail later on but at this point it will be noted that upon counterclockwise movement of pinion 27 in response to raising of the seat 2 or lid 3, or both, the cocking lever 35 engages cocking pin 37 urging timing cam 36 to the left and pulling connecting rod 40 out of hydraulic unit 41. The action of the mechanism is best

seen in FIGS. 9-12 wherein the structure is in an inoperative position in FIG. 9, is initiating its forward stroke in FIG. 10, has completed its forward stroke in FIG. 11 and has gone through a portion of its return stroke in FIG. 12.

Secured to the actuating cam 34 is a pin 45 which is received within a slot 46 formed in the timing cam 36. Since driving pin 32 is received through a slot 47 in actuating cam 34 counterclockwise movement of the driving arm 31 causes the actuating cam 34 to swing also in a counterclockwise direction about its pivot 48 which is mounted on a vertically extending bearing plate 49. As seen in FIG. 10, upon counterclockwise movement of actuating cam 34 pin 45 engages the slanting edge 50 of slot 46 thus urging the timing cam 36 upwardly so that pin 45 enters the straight portion of slot 46 and avoids engagement with the shoulder 51 formed at the upper portion of slot 46.

Pivot pin 39 on timing cam 36 is sufficiently long to be received within a horizontally extending slot 53 formed at one end of a horizontally elongated plate 54 which is bifurcated at its opposite end to provide upper and lower legs 55, 56 which slide on the upper and lower sides respectively of the hub of pinion 27. The free ends of pivot pin 39 also extend through horizontally extending slots 58, 59 formed in a pair of horizontally elongated bracket plates 60, 61 which in turn are secured at their corresponding ends to hydraulic unit 41 by screws 62. This structure insures that the pivot pin 39, and therefore the piston rod 40, are constrained to move along a horizontal path at all times.

As cocking lever 35 urges timing cam 36 to the left as seen in FIGS. 9-12 pivot pin 39 engages the inner end of slot 53 in plate 54 (FIG. 11) and moves plate 54 to the left against the urgency of a tension spring 64 extending between a lug 65 formed along the upper edge of plate 54 and the upper portion of hydraulic unit 41. Cocking lever 35 is urged into engagement with cocking pin 37 at all times by a light tension spring 43 extending between said cocking lever and timing cam 36.

When cocking lever 35 approaches its extreme position (FIG. 11) at which the lid 3 is raised to a vertical position, said cocking lever is swung to a released position relative to cocking pin 37 by the coaction between a cam surface 57 on lever 35 and pin 45 on actuating cam 34. However, before such release is effected, means is provided for holding the lid 3 (and seat 2 if both are raised) in a vertically extending position. Such holding means will now be described.

As best seen in FIG. 3 bolt 12 which secures lid bracket 10 to shaft 8 also secures, by means of nut 68, an elongated pin 69 which may be formed from heavy wire to provide an eye at one end to receive bolt 12 therethrough. When shaft 8 is rotated through 90 degrees as the lid 3 is raised to a vertical position pin 69 is swung from the vertical position of FIGS. 3, 5 to the horizontal position of FIG. 11. As the lid 3 is raised to its vertical position pin 69 is engaged by a hook 71 which is swingably connected at pivot 72 to a plate 73. This plate 73 is formed along one edge 74 so as to be engaged by pivot pin 39 as the latter is moved to the left (FIGS. 9-12) and is swingably mounted on the pivot pin 72 which in turn is secured to an upstanding lug 77 on base 4. Hook 71 is urged in a counterclockwise direction at all times by tension spring 79 extending between said hook and plate 73. However such counterclockwise movement is limited by a stop pin 80 fixed to plate 73. As plate 73 is swung toward pin 69 by the movement of pivot pin 39 to the left said pin 69 engages the upper camming surface of hook 71 and swings the hook clockwise against the urgency of spring 79 so that said hook snaps over pin 69 to the holding position of FIG. 11. By the time cocking lever 35 has been disengaged from pin 37 on timing cam 36, hook 71 is in engagement with pin 69 (FIG. 11) thus holding the lid in its raised vertical position.

Referring now to FIG. 13 it will be noted at this point

that connecting rod 40 is connected to a piston 82 received within a cylinder 83 formed in hydraulic unit 41. As will be pointed out in greater detail later on movement of piston 82 to the right (FIG. 13) under the urgency of spring 64 is damped by the hydraulic fluid within hydraulic unit 41. However it will be apparent that when the lid 3 is in raised position and hook 71 is holding the positioning pin 69, the sliding plate 54 and the piston rod 40 controlled thereby are both held in a locked position by virtue of the position of driving pin 32 relative to the bearing pin 28 (FIG. 11). It is therefore necessary to provide means for reversing the movement of the mechanism so that the piston 82 may move at a controlled rate to the right in FIG. 13 to provide a gradual closing 10 of the lid (and seat if both are connected). Such means is provided by release lever 33 which is interposed between the driving arm 31 and the actuating cam 34. This release lever 33 is provided with a longitudinally extending slot 86 through which driving pin 32 extends. Release lever 20 33 rides on top of the vertically disposed leg 29 which serves as a support for pinion bearing pin 28. Secured to one end of the release lever 33 is one end of a tension spring 87 which is fastened at its other end to a support 88 fixed relative to the base 4. By reference to FIGS. 9-11 25 it will be seen that as the mechanism is moved to its cocked position release lever 33 will be forced downwardly to the position of FIG. 11 under the urgency of driving arm 31 when driving pin 32 engages the end of slot 86 in release lever 33. In the position of FIG. 11 it will 30 therefore be apparent that tension spring 87 exerts a generally upwardly directed force through release lever 33 on driving pin 32. Such upwardly directed force urges driving arm 31 in a clockwise direction and therefore applies a torque to shaft 8 through pinion 27 tending to 35 lower the lid 3. Thus it will be apparent that when piston 82 has moved to the right under the urgency of spring 54 a sufficient distance to release the hook 71 from the pin 69 the torque impressed on shaft 8 by spring 87 will cause the lid 3 to be moved from its vertical position so that it 40 may start downwardly by its own weight. After this movement has been initiated and the driving arm 31 is no longer in a locked position it will be apparent that the resistance offered by the hydraulic fluid in hydraulic unit 41 will regulate the speed at which the lid 3 (and the seat 2 if connected) moves downwardly to its lowered position.

It will be noted when the torque created by the weight of seat 2 or lid 3 is driving the piston to the right as seen in FIG. 12 that the actual driving connection is between pin 45 on actuating cam 34 and shoulder 51 formed 50 along the upper edge of slot 46. Pin 45 engages the shoulder 51 just after sliding plate 54 has traveled a sufficient distance to the right to disconnect hook 71 from pin 69 (FIG. 12). It is for this reason that slot 46 is shaped to provide a straight portion in which pin 45 may 55 move to the right during the cocking movement (FIG. 11); and it is also for this reason that the slanting edge 50 of slot 46 is provided for raising timing cam 36 to the position of FIG. 10.

At this point it will be apparent that means is provided 60 for closing the lid and seat at a predetermined rate of speed after the same have been raised to a vertical position. It is of course necessary to prevent the above described action if a person is seated on seat 2. This is accomplished by the present invention through the use of a 65 brake which is actuated by the weight of such person and which brake will now be described.

The sliding plate 54 is provided with a downwardly extending leg 90 to which is secured a horizontally extending shoe 91 adapted to slide on the upper surface 70 of base 4. Shoe 91 is provided at its outer end with an upwardly extending flange 92 which, as best seen in FIG. 7, extends upwardly to a point just below the bracket 15 of seat 2. As was noted above, seat 2 is provided adjacent its rear end with a yieldable bumper 25 which when the

weight of a person is on seat 2 yields sufficiently to cause the bracket 15 to move downwardly into abutment with the upper edge of flange 92. Thus when the mechanism has moved to its cocked position of FIG. 11 and brake 91 has imparted to it the load on seat 2 then movement of the mechanism to the right is prevented despite the urgency of spring 64. However when the weight is removed from seat 2 the mechanism may then continue its return movement under the urgency of spring 64. In order to avoid interference between brake flange 92 and seat bracket 15 when the mechanism is in its normal position of FIGS. 3, 4 and 9, bracket 15 may be provided with a rectangular notch 95 (FIG. 3) to prevent interference between the bracket 15 and brake flange 92 at the time the seat 2 is raised.

From the above description it will be apparent that there has been provided an effective mechanism which is actuated upon the raising of the lid 3 or raising of the lid 3 and seat 2 and which mechanism provides a time delay after which the lid and seat are closed automatically. In the event a weight is applied to seat 2 then the closing action is arrested until such weight is removed at which time the closing action is automatically set in motion and carried through with the lid closing at a predetermined rate of speed to its horizontal position.

The hydraulic unit illustrated in FIGS. 13 and 14 not only operates as a timer but also provides means for regulating the rate of closing of the lid and seat. Under the urgency of spring 64 the piston 82 is urged to the right within cylinder 83 and escapes from said cylinder through passageway 97 into an internally threaded bore 98 provided with an orifice 99. A horizontal extension 100 of bore 98 leads to a reservoir 101 which in turn is connected to the left hand end of cylinder 83 by passageway 102. The outer end of threaded bore 98 is provided with an internally and exteriorly threaded fitting 105 in which a threaded needle valve 106 is rotatable so as to adjust the clearance between the inner end of needle valve 106 and the orifice 99 thus regulating the speed at which the seat and lid close.

The opposite ends of cylinder 83 are interconnected by a pair of transverse passageways 108, 109 which connect with the longitudinally extending passageway 110. This passageway 110 is restricted as at 111 to form a seat for a ball check 112 which is held in a position closely adjacent restriction 111 by a longitudinally extending screw 113 threadedly received in a fitting 114 secured to the end of passageway 110. By rotating screw 113 the position of ball 112 relative to its seat may be regulated.

If it is desired to lower the lid and seat to their horizontal positions without awaiting the action of the hydraulic unit a release mechanism is provided in a form of an elongated element 115 slidably mounted within the left hand end of bore 110 and provided with a hole 116 in which is received the offset end of a horizontally extending shaft 117 mounted within a fitting 118 and actuatable by a handle 119 for urging the ball 112 away from its seat thus permitting the hydraulic fluid to be bypassed and removing all resistance to lowering of the seat and lid.

The very specific description given above of the preferred form of the invention should not be taken as restrictive as it will be apparent that various modifications in design may be resorted to by those skilled in the art without departing from the scope of the following claims.

I claim:

1. Apparatus for controlling the lowering movement of a member that is adapted to be swung about a horizontal axis from a generally vertical position to a generally horizontal position and vice versa comprising:

holding means for holding said member in said vertical positions,

time delay means for releasing said holding means after a predetermined interval of time after said member has been swung to said vertical position,

means interconnecting said member with said time delay means whereby the moment created by said member when inclined to the vertical is resisted by said time delay means,

whereby the movement of said member from said vertical position to said horizontal position is slowed to a predetermined rate,

and means for arresting action of said time delay means when a weight is applied to said member.

2. Apparatus for controlling the lowering movement of a member that is adapted to be swung about a horizontal axis from a generally vertical position to a generally horizontal position and vice versa comprising:

holding means for holding said member in said vertical position,

time delay means for releasing said holding means after a predetermined interval of time after said member has been swung to said vertical position,

means interconnecting said member with said time delay means whereby the moment created by said member when inclined to the vertical is resisted by said time delay means,

whereby the movement of said member from said vertical position to said horizontal position is slowed to a predetermined rate,

and a spring urging said member away from said vertical position toward said horizontal position to initiate movement of said member away from said vertical position after release of said holding means.

3. Apparatus according to claim 2 wherein said time delay means includes a fluid cylinder and a piston therein, and wherein a linkage is provided for transferring the weight of said member to said piston after movement of said member away from said vertical position, whereby said weight is resisted by said piston to control the rate of downward movement of said member.

4. Apparatus according to claim 1 wherein said time delay means includes a fluid cylinder and a piston therein, and wherein said piston is movable to one of two extreme positions by swinging movement of said member to a vertical position, and wherein said piston moves a substantial distance toward said other position from said one position before said time delay means releases said holding means.

5. Apparatus according to claim 4 wherein said member is interconnected by a linkage with said piston for so resisting said movement.
